J. C. DARST.

SAFETY DEVICE FOR POCKETS,
APPLICATION FILED DEC. 29, 1915.

1,209,942.

Patented Dec. 26, 1916.

UNITED STATES PATENT OFFICE.

JAMES C. DARST, OF PORTSMOUTH, VIRGINIA.

SAFETY DEVICE FOR POCKETS.

1,209,942.

Specification of Letters Patent. Patented Dec. 26, 1916.

Application filed December 29, 1915. Serial No. 69,237.

To all whom it may concern:

Be it known that I, JAMES C. DARST, residing at Portsmouth, in the county of Norfolk and State of Virginia, have invented 5 certain new and useful Improvements in Safety Devices for Pockets, of which the following is a specification.

This invention has for its purpose to provide a simple, and inexpensive safety device 10 for securing valuables in vest and similar pockets, more especially designed as a protector for watch pockets, and adapted for being easily applied to vest and other pockets of wearing apparel; that can be easily 15 and conveniently manipulated with the hand that withdraws the article from the pocket and which, in its application does not mar or change the usual shape or looks of the pocket.

20 My invention also has for its object to provide a pocket protecting device of aluminum, or other light metal, stiff fabric or other suitable material, of a substantially rigid nature, adapted to be secured within 25 the pocket by pasting, stitching or other means, and which, when applied within the pocket may remain in a normal or "locked position" so that the pocket may be used the same as if there was no device in it, and 30 which may be readily adjusted, by finger manipulation, so as to provide a retarding means or guard for keeping the watch within the pocket and prevent its falling out in bending the body while gunning or fishing 35 and also prevent the watch being pulled out by pick-pockets without knowledge of the wearer.

Again, my invention has for its purpose, the provision of a new article of manufacture 40 of a simple and inexpensive character, that may be readily applied in the ordinary pockets of trousers, vests, coats, without any change in the structure of the said pockets.

With other objects in view that will hereinafter appear, my invention consists in the 45 peculiar construction and the novel arrangement of the parts that constitute my improved device, hereinafter fully explained, specifically pointed out in the appended 50 claims, and illustrated in the accompanying drawings, in which:

Figure 1 is a perspective view that shows 55 my pocket guard or safety device as in use in a pocket, the same being adjusted for permitting the watch to be pulled out of the pocket. Fig. 2 is a perspective view of the

device with the parts in a normal position. Fig. 3 is a cross section of a pocket, the guard or safety device being adjusted for holding the watch within the pocket. Fig. 60 4 is a cross section of a pocket and shows the protecting or safety device as held in the normal or closed position, and the pocket adapted to be used in the ordinary manner. Fig. 5 is a horizontal section of the 65 garment, to which the pocket is attached, the device being shown in plan view and in the closed or normal position. Fig. 6 is a detail cross section of one of the spring hinge portions of the device. Fig. 7 is a 70 detail view, of a slightly modified form of my invention hereinafter referred to. Fig. 8 is a detail view of a further modification hereinafter explained.

In carrying out my invention, the safety 75 device consists essentially of a base 1, which may be stamped up, or otherwise formed of metal, such as aluminum, thin sheet steel, stiff fabric, and curved in the horizontal plane to fit snugly on the back part of the 80 pocket, to which it is applied, against the body, as indicated in Fig. 5, and the said member 1 is secured to the inside of the back face of the pocket by stitching 2, as indicated on Fig. 1, whereby it is securely held 85 within the pocket and from being pulled therefrom. The base member 1 fits flatwise in the pocket, as is clearly shown in Fig. 3, by reference to which it will be seen the upper end of the member 1 is bent upon 90 itself to form eye portions 3, that cooperatively fit between similar eye portions 4 on a pair of guard or keeper members 5—5 that fit over the front of the base member 1, the said eye portions 3—4 forming keepers for the hinge pin 6 that extends the full length of the upper edge of the member 1, as shown. Spring hinges 8—8 are mounted on the hinge pin 6 (see Fig. 4) with their free ends held under tension against the back 100 member 1, and the members 5—5, the spring tension being such to normally swing the members 5—5 out from the plate or member 1, as is best shown in Fig. 3. The adjacent ends of the members 5—5 are cut out to form 105 elongated recesses 50—50 which align when the members 5—5 are swung out to form an elongated slot 51 through which the ring post 52 of the watch extends, and in which the said post 52 is adapted to shift laterally 110 when withdrawing the watch from the pocket and the safety device (see Fig.

1); and to provide for freely moving the said ring post 52 as stated, the inner edge of each member 5 is bent back, as at 53.

Normally, my improved device, when attached within the pocket, has the hinged guard members 5—5 closed and locked against the back or base member 1, as is shown in Fig. 4, to thereby permit of using the pocket in the ordinary manner, just the same as if my protecting device was not applied. At such times as the wearer may need protection for example, when fishing or hunting, or in crowds where pick-pockets are to be expected, the wearer, by unlocking the guard members 5—5, permits said members 5—5 to open out to the position shown on Fig. 3, and when thus opened out, the watch may be readily slipped edgewise between the members 5—5 to the position shown in Fig. 3, and when thus positioned it is held from falling out of the pocket and from being pulled out without the wearer's knowledge.

When the device is adjusted, as in Fig. 3, the user may easily lift the watch out of the pocket by closing in one of the hinged members 5 against the back or base member 1 and withdrawing the watch edgewise over the closed member 5 and from under the open member 5, as indicated by the arrow in Fig. 1.

Any suitable finger manipulated means for locking the hinged members 5 to the member 1 may be used. In Figs. 1, 2 and 3, I have shown hooks 7—7 pivotally connected to the said members 5 and having in-turned catches 70—70 that hook over the back member 1, (see Fig. 2). Instead of using the pivoted hook catches 7, the back plate and the member 7 may be stamped up or otherwise provided with the ordinary "glove snap" fastening device 9, as shown in Fig. 7. If desired, the opposing faces of the members 1 and 5 may be lined with chamois skin, as shown by 12 on Fig. 8.

From the foregoing description taken in connection with the drawings, the complete arrangement, the manner of its use and the advantages of my invention will be readily understood.

What I claim is:

1. A protecting attachment for pockets consisting of a rigid member adapted to be attached to the inside of the pocket, and a retaining member hingedly secured at the upper end to the upper end of the rigid member, a spring device normally tending to swing the lower end of the retaining member outward from the rigid member, the said retaining member being adapted to fit over the article held in the pocket, and a finger

releasable means for locking the lower end of the retainer to the rigid member.

2. A protecting attachment for pockets consisting of a rigid member adapted to be attached to the inside of the pocket, and a retaining member, said retaining member being composed of two sections each hingedly secured at the upper end to the upper end of the rigid member, a spring device for each section normally tending to swing the lower ends of the said sections outward from the rigid member, the said retaining members being adapted to fit over the article to be protected, and finger releasable means for locking the lower ends of the retainer sections to the rigid member.

3. A protecting attachment for pockets, consisting of a rigid member adapted to be attached to the inside of the pocket, and a retaining member, said retaining member being composed of two sections each hingedly secured at the upper end to the upper end of the rigid member, a spring device for each section normally tending to swing the lower ends of the said sections outward from the rigid member, the said retaining members being adapted to fit over the article to be protected, finger releasable means for locking the lower ends of the retainer sections to the rigid member, the said retaining sections having their adjacent ends cut out so as to form an elongated slot for the passage of the ring-post of the watch.

4. A protecting attachment for pockets consisting of two members of substantially rigid material, one of such members having its upper edge joined to the upper edge of the other member by a spring hinge connection, said other member being adapted to be secured flatwise on one inside face of the pocket and a finger manipulated locking means for holding the hinged member flatwise against the other member.

5. A protecting attachment for pockets consisting of two members of substantially rigid material, one of such members having its upper edge joined to the upper edge of the other member by a spring hinge connection, said other member being adapted to be secured flatwise on one inside face of the pocket, a finger manipulated locking member for holding the hinged member flatwise against the other member, and said hinge member being composed of two sections, each independently closable against the other member, and a spring hinge connection between each of the said sections and the base member, the opposing edges of the said sections having alining elongated recesses, near their hinged ends.

JAMES C. DARST.
